UNITED STATES PATENT OFFICE.

ALFRED J. SCHWARTZ, OF DETROIT, MICHIGAN.

SILENT SALES STOREROOM FOR PERISHABLE GOODS.

Application filed November 2, 1922. Serial No. 598,586.

To all whom it may concern:

Be it known that I, ALFRED J. SCHWARTZ, a citizen of the United States, residing at Detroit, in the county of Wayne and State 5 of Michigan, have invented a new and useful Silent Sales Storeroom for Perishable Goods, of which the following is a specification, reference being had therein to the accompanying drawing.

10 This invention relates generally to improvements in store service.

An important object of the invention is to provide a truly sanitary construction and selling system whereby perishable goods, 15 such as meats, for instance, may be kept indefinitely in prime condition, and disposed of at retail without unnecessary manipulation on the part of either the vendor or the purchaser.

20 A further object is the provision of means enabling the said goods to be retailed in complete silence, thereby avoiding useless conversations between the buyers and the salespeople, and consequently saving much 25 valuable time to the latter which will permit a corresponding reduction in prices to the former.

With these and other objects in view, the invention consists of the novel improvements, parts, combinations, and features of 30 construction herein shown and described, and pointed out in the subjoined claims.

Referring to the said drawing for a detailed description of the invention,

35 Figure 1 is a top plan view, showing a construction designed to carry out the purposes above indicated; Fig. 2 is a front elevation of the same; and Fig. 3 is an end view.

40 The invention may be practiced in any building or market place where a closed room is available for storing the perishable goods to be sold. Such a structure is indicated in the drawing, in which the reference numerals 11, 12, 13, and 14 represent the outer walls of an ordinary building, 45 and 15 designates a room or compartment therein, which takes up a little more than one-half of the interior of the building and 50 is divided off by suitable partitions, as 16, 17, and 18. The room 15 is intended for the storage and retail sale of meats, fish, fruits, and farm produce of a perishable nature and its dimensions may vary to an 55 indefinite extent. The only requisite, in so far as the size of this store-room is con-

cerned, is that it should embody a staunch construction enabling the space inclosed thereby to be maintained at a relatively low temperature. Ordinarily, it will be sufficient to keep the air in the room at about 35 degrees Fahrenheit in order to preserve all food or provisions stored therein from decay, regardless of the atmospheric conditions either in the rest of the building or 60 outside.

Any preferred means may be utilized to produce the required coolness or refrigeration in the said store-room, whether the same consists of natural or artificial media, 70 and be operated from within or without. By way of example, however, the accompanying drawing suggests the use of a well-known form of refrigerating apparatus including coils of pipe 21, extending lengthwise adjacent to the ceiling of the room, and other mechanical agencies which it is not necessary here to illustrate or describe.

Display-racks 24 are provided, inside the room 15, on which the meats or other articles of food that are put up for sale can be exhibited. A series of such racks is 80 preferably employed, the same following one another in continuous alignment close to the front partition 16, as shown. To 85 refer to the meats only, it is intended, pursuant to the present invention, that they should be cut into pieces or arranged in portions of customary sizes for the retail trade and deposited on platters for display on 90 the racks 24. The latter are furnished for this purpose with several shelves each, which are disposed above one another in step-like formation, but sufficiently spaced apart in a vertical direction to allow the 95 platters to be readily put on and taken off from the interior of the store-room. The arrangement may best be understood by reference to Fig. 3 of the drawing. It is further intended that each piece or portion 100 of meat, and products thereof, should bear a tag or ticket indicating its retail price.

The space immediately behind the display-racks aforesaid, within the store-room, 105 is reserved for the sales people, who are to handle the meat platters, trays, or other containers, and dispose of their contents at the retail prices previously fixed for the same and denoted on the said tags or tickets. The master butchers, with their assistants, will 110 be stationed farther back in the room, at the rear thereof for instance, as indicated by a

meat-cutter's block 27, in Fig. 3. Other attendants may likewise be assigned different stations inside the room, which, it is understood, will have all needed shop equipment, 5 besides the stock of goods subjected to refrigeration.

The partitions 16, 17 and 18, hereinbefore mentioned, are designed to separate the buying public or customers of the establishment 10 selling the perishable goods from the sales people and other persons positioned in the store-room. The intention, it will be perceived, is to keep both the casual buyers and the regular customers entirely out of the room where the perishable goods are 15 stored, exhibited, and offered for sale, so that they can neither gain access to the articles on display, nor have an opportunity to accost and engage in conversation with any one inside. But, to enable the outsiders to 20 inspect the goods before purchasing, and signify their desire to buy such out of the display as will meet their wants, taste or fancy, the said partitions are made so as to 25 transmit all of the light necessary for the displayed articles to be clearly viewed and pointed out. For this purpose, the upper part of each partition is preferably made of 30 glass or other light-transmitting material that will not cause or permit impairment of the refrigeration within the store-room. The lower part of the partitions may consist 35 of woodwork, as indicated at 29, in Figs. 2 and 3. The display-racks may be supported from the woodwork, as shown in the last-named figure, by means of brackets, as 31.

In front of the light-transmitting partitions above described are two aisles 33 and 40 34, set apart in the building containing the store-room for the use of the prospective purchasers of the goods exhibited for sale therein. The first aisle, 33, is next to the building entrances, respectively marked 36 and 37, in Fig. 1, and may be called the 45 observers' aisle, as a full view of the goods on the display-racks behind the partitions can be had from it, sufficient to apprise those who have entered the place of the particular shelf or shelves where the articles that they want are to be found and enable them to decide, after seeing the price tags affixed to the same, as to whether or not they will purchase. The other aisle, 34, runs in close 50 proximity to the partitions, and may be termed the purchasers' aisle. The two aisles are separated by simple railing, as 39, set up in short lengths that permit quick passage at convenient intervals from one aisle 55 to the other, in approaching a chosen display-rack or leaving it when a purchase is completed.

In accordance with the improved selling method contemplated by the invention, the 60 intending purchasers who advance into the

aisle 34 are given each a ticket bearing a certain number, and at the same time the sales people or attendants in charge of the display-racks behind the light-transmitting partitions are directed to provide empty 70 trays identified by corresponding numbers. A patron showing the ticket received can therefore be waited on by a person carrying the tray marked with the same number, into which will be deposited such of the 75 displayed goods as the former points out to the latter. As soon as an article has been selected and bought, the numbered tray containing it is placed upon an endless belt conveyor 41, located a little below the low- 80 ermost shelves of the display-racks and serving to transfer the laden trays onto a wrappers' table 42, situated at one end of the store-room, for instance the right, as shown in Fig. 1. By preference, the belt is run 85 continuously in the same direction and very slowly, so that a customer may have sufficient time to make a desirable selection of the goods exhibited on any of the racks, or to buy articles to be taken off several racks, 90 while the tray carrying the purchases moves toward its destination.

Another conveyor 45, of the parcel carrier type, is provided for the accommodation of those who make all of their purchases at the farthest display racks or stands 95 from the wrapping table, or who buy but one article and naturally desire to take it out as promptly as possible. This other conveyor is suspended by hangers 46, from 100 the ceiling of the store-room 15, at some distance above the display-racks 24, and being thus located overhead, it can be safely run at a much faster speed than the belt below, so that the goods placed in a tray or 105 basket attached to it can be brought instantly to the table 42, to be wrapped up and delivered.

The goods that have been sold and wrapped up are passed out, through a 110 wicket or drop-window 49, provided in the partition 18, onto a delivery counter 51, located exteriorly of the store-room. The packages that are ready for delivery, it is understood, bear indications of the prices 115 to be paid for the same, the amount in each instance being reckoned from the figures appearing on the tags affixed to the goods displayed. A cashier's stand or cage 52 is at the end of the alleys 33, 34, by the counter 120 51, and the amounts payable on the articles sold are collected there, as each package is being handed out. Thence the patrons of the establishment can leave the building 125 through a near-by exit, as 53.

Having described my invention, what I claim, and desire to secure by Letters Patent of the United States, is:—

1. A selling system for perishable goods comprising a store-room maintained at a 130

- relatively low temperature, means for displaying the goods together with their retail price therein, a light-transmitting partition between the vendor and purchaser 5 through which the said goods may be viewed and pointed out, a conveyor arranged to transfer indicated articles to a place of delivery, and a means of egress enabling said articles to be passed out of the store-room.
- 10 2. A silent sales store-room including a refrigerated inclosure, a series of devices of open step-like formation therein adapted for the display of perishable goods with prices thereto affixed, a light-transmitting partition 15 in front of said devices affording a full view of said goods and prices, a conveyor adjacent the series of devices behind said partition, and a closure in the latter permitting delivery of the goods in packages from 20 the said store-room to persons outside.
3. A structure of the character described including a closed store-room, means for cooling the atmosphere therein, a line of display racks in said store-room adapted to exhibit perishable goods with price tags thereto attached, a light transmitting partition in front of said racks allowing said goods and prices to be seen exteriorly thereof, a slow moving conveyor passing by the lower part of the line of racks in rear of 25 said partition, a rapid carrier arranged to run above said conveyor, a wrapping table for doing up packages of goods received from either the conveyor or the carrier, a delivery counter on the opposite side of the 30 partition from said table, and a wicket in the partition affording a passage from the table to said counter.

ALFRED J. SCHWARTZ. [L.S.]
